SYRINGE

Charles A. Gray, 2334 Scott St., Hollywood, Fla.

Filed Apr. 22, 1965, Ser. No. 84,920

Term of patent 3½ years

(Cl. D83—12)

FIG. 2.

FIG. 1.

FIG. 5.

FIG. 4.

FIG. 3.

FIG. 6.

FIG. 7.

FIG. 1 is a front elevation of a syringe showing my new design;

FIG. 2 is a top plan view thereof;

FIG. 3 is a side elevation thereof;

FIG. 4 is a bottom plan view thereof;

FIG. 5 is a top plan view of a modified form shown in FIG. 1;

FIG. 6 is a front elevation of the modified form of syringe shown in FIG. 1; and

FIG. 7 is a perspective view of a further modification of the embodiment shown in FIG. 1.

The dominant features of my design reside in the portions shown in full lines.

I claim:

The ornamental design for a syringe, substantially as shown and described.
